UNITED STATES PATENT OFFICE.

WARREN C. SCHERER AND EVELYN D. SCHERER, OF BUFFALO, NEW YORK.

HAIR FORM.

Application filed March 29, 1922. Serial No. 547,639.

To all whom it may concern:

Be it known that we, WARREN C. SCHERER and EVELYN D. SCHERER, citizens of the United States, residing at Buffalo, in the 5 county of Erie and State of New York, have invented certain new and useful Improvements in Hair Forms, of which the following is a specification.

Our invention relates to hair forms of the 10 type employed in dressing the hair.

Hair forms of this type are usually in the shape of a skeleton frame having a base adapted to rest upon the head, and a super-structure or crown rising from the base and 15 spaced from the head so that when dressing the hair over the form to produce a roll or knotted effect, the form is concealed and the effect of the dressed hair is such that it appears to be completely formed of the flowing strands of hair without the use of a false 20 foundation.

The present style of dressing hair calls for a considerable projection of the hair from the head, and hair forms now in use 25 make it extremely difficult to properly and conveniently wear a hat over the rolled or knotted projecting portion of the hair dressed over the form. In placing the hat in proper position on the head, it is often 30 necessary to shift the rolled, knotted, or otherwise dressed projecting portion of the hair out of the position in which it was originally placed, and due to the fact that the hair form underneath the dressed hair 35 is firmly secured to the head and the hair form is not capable of collapsing or yielding to pressure or strain, such as applied when shifting the hat to the desired position, the portions of the hair adjacent the head 40 will be pulled upon and create an annoying sensation, and oftentimes pain.

It has also been experienced that in applying strain or pressure against the dressed hair when placing the hat in position, the 45 hair becomes undone; and when removing the hat, the hair has a disheveled and at times even an unsightly appearance, caused by the ends of the long strands projecting from the roll, knot, or other dressed portion 50 of the hair. This gives the dressed portion of the hair a feeling of looseness on the head, which is also uncomfortable and annoying.

The primary object of our invention is to 55 provide a hair form which is collapsible transversely; or with respect to its position on the head, upwardly and downwardly, or

forwardly and rearwardly, depending on the exact location of the form, as the location will vary according to the style in which the hair is dressed.

A further object of our invention is to provide a simple and inexpensive hair form which will enable the hair to be dressed in a more effective manner and with greater projection from the head than possible with other forms, due to the fact that its collapsibility will permit its being made longer than present types of forms and will also permit the proper placing of a hat on the head and the wearing of the hat with greatest convenience, as the hair and the form over which the hair is dressed will easily yield to the pressure of the hat and as quickly recover itself when removing the hat without loosening or disarranging the dressed portion of the hair.

A further object of our invention is the provision of a hair form which, although designed to be used with its length transversely of the head, may be used with its length up 80 and down or forwardly and rearwardly on the head.

A further object of our invention is to provide a form which in addition to being collapsible transversely is so constructed that 85 its crown will yield inwardly toward the head so that, in a sense, the crown is universally yielding; the form having its frame constructed of springy wire which when yielding under pressure in any direction will 90 recover its normal shape when relieved of pressure.

Further objects and advantages of our improved form will appear from the following 95 description taken in connection with the accompanying drawings.

The invention consists in a hair form having a base, and a universally yielding crown.

It also consists in a hair form transversely collapsible; and in the novel features of 100 construction and arrangement of parts to be hereinafter described and more particularly pointed out in the subjoined claims.

In the drawings:—

Fig. 1 is an illustration showing the manner in which our improved hair form is applied to the head and the hair dressed over the same; this being, however, merely one of many styles in which the hair may be dressed over the form and one of several locations 110 in which the form may be placed.

Fig. 2 is a top plan view of the form.

Fig. 3 is a side elevation of the same.

Fig. 4 is an end view showing in dotted lines the manner in which the form may be collapsed transversely.

5 Fig. 5 is a perspective view of the form.

As preferably constructed, the form is built up of three pieces of wire, more or less springy in nature and preferably thread or cloth-covered, one of said wires forming 10 the base and the remaining two the crown.

The form, viewed from the side, is substantially of crescent formation and it comprises a base 6 and a crown 7. The base has opposite laterally and outwardly curved 15 side members 8, 9 joined together at opposite ends of the base by sharply rounded portions 10, 11. This base is formed of a single piece of wire, and is in the form of a loop the ends of the wire being overlapped 20 between the ends of one of the side members and secured together in any approved manner. The outward curve of the side members gives the base a longitudinally extended curvature so that it will conform to the 25 shape of the head. While the lateral curvature of said side members provides the desired width at the central portion of the base, the base being therefore gradually widened from opposite ends towards its 30 transverse center.

The under side of the base may be said to be concaved to conform to the convexity of the head so that it will fit snugly against the hair of the head when combed evenly, 35 with the long strands hanging down the rear in loose form, to be tied together by means of a suitable tie, rubber band, or other device in close proximity to the form.

The crown 7 is constructed of two wires 40 12, 13 to form two sections, each section having opposite ends fastened to one of the side members of the base, as at 14. Each crown section comprises a long curved member 15 extending from a point of one side member of the base considerably closer to one end thereof than the other and being directed outwardly from the base and toward the opposite end thereof and thence recurved, as at 16, into a comparatively short 50 member 17, the extremity of which is fastened to the same side member. These crown sections trend in the same general direction as the side members of the loop-like base and lie in contact with each other 55 adjacent their recurved portions 16 and are connected together, as at 18, a short piece of wire or other material being used for this purpose. The crown sections may therefore be said to overlap each other and 60 be tied together at the overlapping portions, and as the ends of the curved wires forming the crown sections are secured, respectively, to opposite side members of the base, the side members of the base may be collapsed 65 or moved toward each other, while the se-

cured inner ends of the crown sections move outwardly and inwardly with said side members.

It is to be noted that each crown section is secured to a base member at one side of the transverse center of said base member and that the recurved portions 16 of said crown sections extend beyond said center, said recurved portions serving as spring portions which permit the crown members 75 to be pressed toward the head or, in other words, yield inwardly, without changing the relative positions of the side member of the base, and without causing the wires forming said crown members to buckle upon 80 themselves.

From the foregoing it will be apparent that our improved hair form can be collapsed transversely; also that the crown portion may be flexed inwardly or toward 85 the head, or both of these actions may take place at the same time, for which reason we consider and term our hair form one that is universally yielding.

Examination of Fig. 2 of the drawings 90 will show that when the hair form collapses transversely, the short members of the crown actions move toward the longitudinal center of the base to a greater degree than the long members, owing to said short members 95 being connected to a wider portion of the base than the long members; also that the recurved portions of the crown sections permit the crown to yield inwardly under pressure.

Our improved hair form is preferably covered with wool crêpe or other imitation hair, which is manufactured in various colors or shades so that a form may be purchased having a color or shade which will 105 match the hair with which it is to be used.

When the form is placed against the head and the depending long strands of hair are tied together at a point adjacent the form (which tying may be accomplished 110 before or after securing the form in place), the depending hair can be placed over the form in any desired style or, if desired, the depending portion of the hair may be placed partly around the form before placing the form against the head and the free ends of the hair then dressed in any desired style and fastened into or under the form by means of hairpins or otherwise.

In the event that, through carelessness or 115 otherwise, the hair does not fully cover the form, the imitation hair covering of the form will be disclosed, but as this matches the hair it would be very difficult to detect.

Our improved hair form may be used in 120 various ways, and while we have shown the same arranged with its length crosswise of the head and at the rear, it may be arranged crosswise on top of the head, or may be arranged lengthwise to reach partly onto the 125 130

top of the head and partly over the rear of the head. In each case, however, when the hair is dressed over the form in desired style, a neat appearing extended portion of 5 the hair is provided on the head, which has the appearance of being formed completely of natural hair.

Having thus described our invention, what we claim is:—

10 1. A hair form or frame formed of wire and having a base and a crown portion, said crown portion comprising two sections, each being secured to said base at one side of the transverse center of the latter.

15 2. A hair form or frame comprising a base, and a crown portion comprising two sections arranged at opposite sides of the longitudinal center of said base and connected together so that said crown portion may

20 flex laterally in either direction.

3. A hair form or frame comprising a base having spaced side members, and a crown comprising two sections secured, respectively, to opposite side members of the 25 base and fastened together in a plane between said side members.

4. A hair form or frame formed of wire having a base concaved in the direction of its length, said base having opposite spaced 30 side members, and a crown formed of two sections connected to opposite side members of the base at opposite sides of a plane passing transversely through the base and having portions overlapped and tied together at 35 said overlapping portions.

5. A crown member having a base formed 40 of wire fashioned to provide two spaced curved side members connected together at their ends and gradually curved laterally from their ends toward the transverse center of the base, and a crown formed of two sections, each comprising a wire curved between its ends to form a long member and a short portion terminating at and secured to 45 one of the side members of the base, said crown sections being secured to the base at opposite sides of a plane passing midway through the base and having their curved portions overlapping and connected together in a plane passing longitudi-

dinally between the side members of said base.

6. A hair form or frame comprising an elongated base gradually narrowed from its center toward its ends and curved longitudinally to conform to the shape of a head, crown sections extending upwardly from opposite sides of said base and overlapping at the highest portion of the crown, and means for connecting the overlapping portions of said crown sections together. 55

7. A hair form or frame comprising a base, and a crown portion consisting of two sections secured to opposite sides of said base and connected together in a plane passing lengthwise centrally through said form or frame, said sections being secured to said base at opposite sides of a plane passing transversely through the latter. 65

8. A hair form or frame formed of wire 70 and comprising an elongated loop-like base and a crown formed of two connected parts, each part being formed of a piece of wire curved upon itself and having opposite ends fastened to one side of said base. 75

9. A hair form or frame formed of wire comprising a base having two side members movable toward and from each other, and a crown formed of two parts fastened to opposite side members of said base and to each other in a plane between said side members. 80

10. A hair form or frame comprising a base having outwardly-curved side members meeting at the ends of the base, and a crown comprising two members attached to opposite side members of said base and trending in the general direction of said side members so that said crown may collapse laterally. 85

11. A hair form or frame formed of wire and comprising a base and a crown having 90 two members connected to opposite sides of said base, each of said crown members being formed of a single piece of wire curved upon itself to form a long member and a short member so that the crown may collapse inwardly. 95

In testimony whereof we affix our signatures.
